UNITED STATES PATENT OFFICE.

THOMAS F. CARPENTER, OF DERBY, OHIO.

MACHINE FOR WEAVING CROSS-WIRES IN FENCES.

SPECIFICATION forming part of Letters Patent No. 643,109, dated February 13, 1900.

Application filed June 14, 1899. Serial No. 720,456. (No model.)

To all whom it may concern:

Be it known that I, THOMAS F. CARPENTER, a citizen of the United States, residing at Derby, in the county of Pickaway and State of Ohio, 5 have invented a certain new and useful Improvement in Machines for Weaving Cross-Wires in Fences, of which the following is a specification.

My invention relates to machines for weaving cross-wires in fences; and the objects of my invention are to provide an effective cross-wire-weaving mechanism for wire fences which shall be simple of construction and capable of being rapidly and easily operated, 10 to so construct the same as to admit of the cross-wire being wound in either direction about the longitudinal wires, and to produce other improvements, the details of construction and arrangement of parts of which will 15 be more fully pointed out hereinafter. These objects I accomplish in the manner illustrated in the accompanying drawings, in which—

Figure 1 is a view of a portion of a wire fence, showing my machine in position for 20 weaving the cross-wire therein. Fig. 2 is a detail view in perspective of the upper portion of the shifting frame. Fig. 3 is a plan view of the weaver, showing the main operating gear-wheel cut centrally. Fig. 4 is a detail view in perspective of the sliding block or 25 head, which I employ in the manner hereinafter described. Fig. 5 is an end view of the weaver-tube and its beveled pinion; and Fig. 30 6 is an end view of the catch-lever, which I employ in the manner hereinafter described.

Similar numerals refer to similar parts throughout the several views.

In carrying out my invention I employ a shifting weaver-supporting frame 1, which 40 consists of two vertical and parallel angle-bars 2, which are suitably connected by transverse bolts 3'. The outwardly-projecting vertical wings of the angle-bars 2, which are indicated at 3, are provided with oppositely-located edge recesses 4, which are arranged at suitable distances one from the other and which are adapted to receive the horizontal wires 5 of a wire fence. The shifting frame thus produced is adapted to be retained, in 45 connection with the fence, in the position described through the medium of a vertical retaining-rod 6, which extends through suitable

eyes or staples 7, which project from the outer side of one of the bar-wings 3 at points on the outer sides of the inner ends of the recesses 4. 55

8 represents a sliding block the vertical edges of which are recessed, as indicated at 8^a, to receive the edges of the inturned wing portions 3^a of the angular standards 2, said standard portions being thus made to loosely 60 embrace said block 8. Pivoted to and on the outer side of said block is an outwardly-extending weaver-supporting arm 9, the latter having its outer portion bent at an angle with its remaining portion. The angular arm 9 65 thus formed is jointedly connected at 10 with the outwardly-extending arms of two angular yoke-bars 11, the latter embracing loosely and having its remaining end portions connected, respectively, with the upper and lower sides 70 of a lateral extension 12 of a horizontal weaver-tube casing or boxing 13. As indicated more clearly in Fig. 3 of the drawings, I provide those ends of the arms or bars 11 which are jointedly connected with the arm or bar 9 with 75 separated projecting lugs 14 and 15, which are adapted to engage opposite sides of a lug 16, which is formed on said arm 9 in such position as to contact with the lugs 15 and 14 when said arms 11 are swung in either direction 80 independently of the arm 9, thus limiting such independent swinging movement.

As is usual in this class of weavers, the weaver-tube casing is provided throughout its length with a longitudinal slot or opening, which is indicated at 17, and within the casing or boxing thus formed is journaled a weaver-tube 18, the latter having on its outer end portion a head or flange 19 and carrying on its opposite end portion a bevel-pinion 20. 90 The tube 18 is also provided with a longitudinal slotted opening, which is indicated at 21, and that end portion of said tube which projects through the pinion 20, which is carried thereon, is surrounded by a clip 22, having an entrance or mouth portion which is opposite said tube-slot opening 21. As indicated at 12^a, the lateral projection 12 of the weaver casing or boxing is provided with an outwardly-extending frame-bar which is bent 95 to a substantially yoke shape and the outer termination of which is in the form of a suitable handle 12^b. From the center of the length of the frame-bar 12^a thus formed pro-

jects a pin 23, on which is rotatably mounted the hub portion of a bevel gear-wheel 24, the latter extending at right angles and gearing with the pinion 20. The gear-wheel 24 is also provided with a crank-handle which projects from a point near the rim of said wheel and is indicated at 25. At a point on the periphery of the wheel 24 I provide a projecting pin 26, with which is adapted to be engaged the concaved or recessed end of a spring-actuated catch-lever 27, the latter being fulcrumed on one side of the handle 12^b and having its recessed end normally depressed and in the path of said pin 26. Projecting outward from the flange 19 is a pin 28, on which is adapted to be supported a coil of wire, such as is indicated at 29 in Fig. 1.

In order to illustrate the operation of my device, we will assume that the shifting-frame standards 2 are connected with the longitudinal wires of the fence in the manner shown and heretofore described and that the block or head 8 is in its position between the wings 3^a of said standards. The wire from the coil 29 leads from said coil in the usual manner through the tube 18, and the weaver is turned in the direction of the length of the fence, causing the adjoining longitudinal fence-wire 5 to enter said weaver-tube through the slotted openings 17 and 21. The wire 29 having previously been attached, as shown in Fig. 1, to an upper wire 5, it is obvious that a rotation of the gear-wheel 24 must result in a winding action of the wire 29 about the adjacent wire 5. In constructing my machine the relative sizes of the wheels 24 and 20 are preferably such as to cause from two to three wraps of the cross-wire about the longitudinal wire at one complete revolution of the gear-wheel 24. This revolution being completed, the wheel may be held in place by causing an engagement of the catch-lever 27 and the pin 26. In continuing the weaving operation the machine is now swung outward on the pivot 10 to cause a disengagement of the horizontal fence-wire last operated upon and the weaving-tube. Having been thus swung outward, the weaving-machine is dropped to the next lower wire 5, where the operation above described is repeated. In this downward movement it is obvious that the block 8 will travel between the frame-standards 2 of the shifting frame. It will readily be seen that in order to drop the machine to the next succeeding wire a certain proportion of the wire

29 must be reeled off or unwound from the pin 28 and that this unwinding or gaining of slack wire is produced by the outward-swinging movement of the weaver. In order to prevent a direct pull on the horizontal wire 60 previously operated upon when the machine is swung outward, I have provided the joint 10 between the arms 9 and 11, this joint admitting of the weaver-body being swung outward and a portion of the wire unwound from 65 the pin 28 before the lug 15 comes into contact with the lug 16 of said jointed arms, thus providing a limited amount of slack wire before the swinging movement is imparted to the arm 9.

When the cross-wire has been in the manner above described carried from the top to the bottom horizontal wire, it is obvious that the shifting frame 1 may be moved in the direction of the length of the fence before again 75 beginning the operation of weaving said cross-wire in connection with said horizontal wire.

It will be observed that the operating gear-wheel 24 may be turned in either direction, thus admitting of the winding action of the 80 wire 29 upon the wires 5 being reversed as desired.

Having now fully described my invention, what I claim, and desire to secure by Letters Patent, is—

In a machine for weaving cross-wires in fences, the combination with a shifting frame consisting of united parallel standards 2 having slotted recesses for the reception of the longitudinal fence-wires, a weaver-frame, a 90 slotted tube boxing or casing, and a handle portion formed therewith, of a slotted weaver-tube journaled in said casing, a wire-carrying pin projecting as described from said tube-flange, a slotted pinion on said tube, a bevel gear-wheel journaled on said weaver-frame and gearing with said pinion, said gear-wheel having a handle projection, yoke-arms 11 having corresponding ends connected with said weaver-frame and extending on opposite sides 100 of said pinion, a block 8 having a sliding support between the standards of said shifting frame and an arm 9 jointedly connected at one end with the block 8 and having its remaining end jointedly connected with said 105 yoke-arms 11, substantially as described.

THOMAS F. CARPENTER.
